CLAIM

An ornamental design for a grippable beverage bottle, as shown and described.

DESCRIPTION

FIG. 1 is a top perspective view of a grippable beverage bottle;

FIG. 2 is a rear elevation view of the embodiment shown in FIG. 1;

FIG. 3 is a front elevation view of the embodiment shown in FIG. 1;

FIG. 4 is a side elevation view of the embodiment shown in FIG. 1 (the opposing side elevation view would be a mirror image of the side elevation view shown in FIG. 4); and, FIG. 5 is a top plan view of the embodiment shown in FIG. 1.

The dotted lines shown in FIGS. 1-5 are for illustrative purposes only and form no part of the claimed design. The dot-dash-dot line shown in FIGS. 1 & 5 defines the boundary of the claim.
